UNITED STATES PATENT OFFICE.

ALFRED W. BURKE, OF PELHAM MANOR, NEW YORK.

WASHING MACHINE.

REISSUED

Application filed December 21, 1921. Serial No. 523,820.

My invention relates to an improvement in washing machines and an object thereof is to improve and simplify the construction of washing machines as now constructed and 5 to increase their efficiency.

In general, my improved device comprises an apparatus wherein a vacuum or reduced pressure is employed to agitate the clothes or other articles to be washed.

10 In the accompanying drawings,—

Fig. 1 shows an embodiment of my improved device in part sectional elevation; and

15 Fig. 2 is a part sectional elevation of a modified form thereof.

Referring to the drawings in detail,—1 designates what I shall hereinafter refer to as a main tank which is provided with a cover 2 adapted to be secured thereto by 20 any suitable means such as quick acting clamps 3 for example. The cover is substantially an air-tight fit. The bottom of the tank is provided with perforations as indicated at 4 for a purpose to be better pointed

25 out hereafter. The tank 1 is mounted on legs 5 within an auxiliary tank 6 and in spaced relation thereto, the auxiliary tank being supported as upon legs 7 or in any other suitable manner. Mounted adjacent

30 the main tank, in the present instance upon a bracket 8 secured to the side of the auxiliary tank 6 is a motor 9 for driving a vacuum fan 10. Connected to the intake side of this fan is a pipe 11 passing into or 35 through the wall of the main tank 1 so as to be in communication with the interior thereof. The vacuum apparatus is provided with a return side 12 here shown as a pipe, this pipe communicating with the auxiliary tank

40 6 at some point below the level of the device 10. For convenience I have shown the return pipe 12 entering the auxiliary tank 6 at a point adjacent the bottom thereof.

In operation the water is placed in the 45 tank 6 and flows through the perforations 4 in the bottom of the tank 1 until the desired level is reached. The clothes or other articles to be washed may then be placed in the main tank and the cover 2 clamped down.

50 The motor 9 may now be operated to drive the vacuum fan to create a vacuum within the tank 1. This reduction of pressure within the main tank causes a rise in the level of the water in the tank 1, water flowing from the tank 6 until the level of the water in the latter is adjacent the bottom

of the main tank. Of course this reduction in pressure causes great agitation in the tank 1 due to air being drawn out of the water and this agitation continues due to 60 air being constantly drawn from the atmosphere through the water in the main tank. I preferably apply the vacuum intermittently by intermittent operation of the motor 9 so that at certain intervals the body 65 of water in the main tank will rise and fall due to the intermittent application of the vacuum, this surging effecting further agitation of the articles being washed. The combined action of the air passing through 70 and around the articles being washed and the surging of the water in the main tank effect the desired cleansing. Any water or suds which may be drawn into the device 10 will be returned to the auxiliary tank 6 by 75 way of the return pipe 12. In this way after the machine is filled to the desired degree with water no further attention need be paid to it until the washing operation is completed.

80 In the modification shown in Fig. 2 I provide a main tank 13, the bottom of which, to one side of the center thereof is perforated as indicated at 14. This tank likewise is provided with a cover 15 having a 85 substantially airtight fit with the tank and held in place by quick acting clamps 16. This tank is mounted upon legs 17 within an auxiliary tank 18 similar to the tank 6 of Fig. 1. The interior of the main tank 90 13 is provided with a trap 19 for sediment, this trap comprising a baffle 20 at the bottom of the tank to one side of the perforations 14, the upper edge of this baffle being spaced a short distance from the bottom of 95 the tank. Extending from the upper edge of the baffle 20 to the side of the tank 13 is a plate 21 perforated as indicated at 22. The plate 21, baffle 20 and a portion of the bottom of the tank 13 constitute the walls 100 of a compartment or chamber which I have referred to above as a trap for sediment and which I have designated 19. Leading from this trap is a pipe 23 conveniently controlled by a valve 24 by which the sediment in the 105 trap may be withdrawn.

110 Mounted upon one wall of the tank 18 is a bracket 25 supporting a motor 26 provided for the purpose of driving a vacuum fan 27. The intake side of this fan is connected to the interior of the tank 13 by a pipe 28 while the return side is connected

to the tank 18 by return pipe 29. The operation of this device is very similar to that of the device of Fig. 1. As the motor 26 is put in operation after the tank 18 has been filled to the desired degree with water a vacuum will be created on the interior of the tank 13 to cause an agitation of the water and clothes or other articles therein. Inasmuch as the tank 18 is an open tank 10 air will be drawn through the water therein and through the perforations 14 in the tank 13. As these perforations are at one side of the tank 13 the air being drawn through the perforations will tend to upset the 15 articles being washed, thereby insuring a very thorough agitation of these articles. The sediment from the clothes or other articles being washed settles in the trap 19 passing into this trap through the perforations 22. In this arrangement of course the suds and water which are drawn into the fan 27 are returned to the tank 18 by way of the return pipe 29 so that it is unnecessary to refill the tank 18 until the washing 25 operation is completed.

It will be seen from the foregoing that I have provided a machine for washing purposes wherein a reduction in pressure or partial vacuum within the tank containing 30 the articles to be washed is relied upon for effecting the desired agitation of the articles being washed and that for this reason the wear and tear on these articles is very much reduced as compared with the mechanical 35 devices now employed.

While I have shown a specific embodiment of my invention it is to be understood, however, that changes may be made in the details thereof within the purview of my invention.

What is claimed as new is:

1. In combination, an auxiliary tank, a main tank disposed therein and in spaced relation thereto, one wall of said main tank being perforated, a bracket carried by the auxiliary tank, a motor supported on said bracket, a vacuum fan driven by said motor, the intake side of said fan being in communication with the interior of said main tank and the return side of said fan being 50 in communication with the interior of the auxiliary tank.

2. In combination, a closed tank provided with a perforated bottom, an open auxiliary tank within which the main tank is mounted 55 in spaced relation thereto, a motor driven vacuum fan supported by one of said tanks and means for establishing communication between the intake side of said fan and the interior of said main tank and between the 60 return side of said fan and the interior of said auxiliary tank.

3. In combination, an open auxiliary tank containing a liquid, a main tank within said auxiliary tank and in spaced relation thereto, the bottom of said main tank being provided with perforations, a bracket carried by said auxiliary tank, a motor supported on said bracket, a vacuum fan connected to said motor, a pipe leading from said fan 70 to the interior of said main tank and an additional pipe leading from said fan to the interior of said auxiliary tank whereby air may be drawn through the liquid in the auxiliary tank and through the perforations 75 in the main tank and through the liquid in said main tank, any liquid passing to said fan being returned to said auxiliary tank.

This specification signed this 17th day of 80 December, 1921.

ALFRED W. BURKE.
